Charles W. Mortimer, Inventor.

UNITED STATES PATENT OFFICE

CHARLES W. MORTIMER, OF UPPER MONTCLAIR, NEW JERSEY, ASSIGNOR TO THE BARRETT COMPANY, A CORPORATION OF NEW JERSEY

SHINGLE AND METHOD OF CUTTING THE SAME

Application filed July 9, 1924. Serial No. 724,939.

This invention relates to a shingle or shingle strip and the process of cutting the same from a sheet of roofing material. It relates more particularly to the sort of shingle that is cut from a roofing sheet that is made by saturating a so-called felt base with waterproofing material such as asphalt, coating the same with plastic material such as asphalt, for example, and applying thereto a layer of wear-resisting material such as crushed stone, slate, etc.

By the present invention, shingles or shingle strips are produced which have projecting tabs along one edge with spaces therebetween so that the shingle can be installed on a roof in such a manner that six-sided or hexagon shaped figures will be exposed to the observer. It has been found that in installing shingles or shingle strips of this sort there is danger of leakage occurring at the joints made by laying the shingles in horizontal rows on the roof. By the present invention the joints are made more secure against leakage without detracting from the attractive design of the shingle. At the same time the shingles or shingle strips may be cut from sheets of roofing material without any waste of material.

The invention will be understood from the description in connection with the accompanying drawings, in which

Fig. 1 is a plan view showing how the shingles may be cut from a sheet of roofing material;

Fig. 2 is a plan view of a modification;

Fig. 3 is a plan view of a second modification; and

Fig. 4 is a plan view showing how the shingles may be installed upon a roof.

In the drawings reference character A indicates a sheet or strip of roofing material having parallel sides which may be cut along the zig-zag lines 1, 2 and 3 at intervals. The lines 2 join the lines 1 and 3 preferably at the same angle which the lines 1 and 3 make with the edges of the roofing strip so that the sides of the tabs or projections 4 are bounded by converging lines, the lines 1 and 3 being of the same length. The strips A are also severed half way between the sides of lines 1, 2 and 3 along lines 5, 6, 7, 8, 9, 10 and 11 so that

rectangularly shaped projections 12 are left on the edges of the body portion of the shingles opposite the tabs 4 to one side of the middle point of these edges.

Instead of having the projections 12 of rectangular shape as just described the shingles may be cut from a roofing strip along serpentine lines as shown at 13 and 14 (Fig. 2) thus producing semi-circular projections or projections having other curved outlines. Or the strips can be cut transversely as shown at 15, 16 and 17 (Fig. 3) to produce triangular shaped projections. The projections just described are preferably spaced so that the central portion or highest part thereof is placed a distance from the central point of this edge equal to one-half the distance the line 2 measures along lines parallel to lines 1 and 3. That is, the width of the projections 12, etc., should equal one-fourth the difference between the widest and the narrowest portions of the tabs 4.

In installing these shingles upon a roof, horizontal rows of the same are laid as shown at 1, 1' and 1² (Fig. 4) with their horizontal ends abutting. The series 1' is laid so that the ends 18 of their tabs coincide with the lines 19 along the lower side of the narrow portion of the shingles. Their wide ends 20 then extend across the middle portion of the extensions or projections 12 of shingles in the subjacent row.

The protection afforded by the projections 12 is obvious when the projection designated by the reference character 12 in Fig. 4 is observed. It is obvious that if the tab 4² in the third row should be blown up by the wind there would be only a short distance for water to travel along the dotted lines 21 before it would reach the line 22 of the usual shingle and cause leakage. However, with the projection 12 underlying the joint made by the lines 21, the water has this much greater distance to travel upwardly before getting under the shingle.

The lower edge of the narrow portion of the shingles in the row 1' may be nailed down to prevent the same from curling up by driving nails through the same near the pointed corner of the shingle as the nail heads

would be covered by the tabs 4 of a higher row of shingles and since these portions of the shingles 1' are closely held down the danger of water being blown upwardly into the indentation P corresponding to the projection 12 is minimized.

It is obvious that instead of having a roofing sheet of sufficient width to produce single shingles as above described, the roofing sheet 10 may be made wide enough to produce a plurality of shingles joined end to end or so-called "multi-shingles". In such a case it would not be necessary to provide projections on the edges opposite the shingle tabs in number to 15 correspond to the number of shingle tabs on the strip. The projections along the upper edges of the shingles are needed only where there are joints to be protected so that it is sufficient to have a projection along the 20 upper edge for each shingle or for each shingle strip or multi-shingle.

I claim:

1. In a shingle, a main body portion, a tab along one edge and at one end of the 25 said body portion adapted to be exposed to the weather when a number of said shingles are laid upon a roof and a weathering projection on the other edge approximately in line with one end of said tab.

30 2. In a shingle, a main body portion, a tab along one edge and at one end of the said body portion adapted to be exposed to the weather when a number of said shingles are laid upon a roof and a weathering projection and an indentation along the other 35 edge approximately in line with one end of said tab.

3. In a shingle, a main body portion, a tab along one edge and at one end of the said 40 body portion adapted to be exposed to the weather when a number of said shingles are laid upon a roof and a weathering projection and an indentation contiguous to each other and of substantially the same size and shape 45 along the other edge approximately in line with one end of said tab.

4. In a shingle, a main body portion, a tab along one edge and at one end of the said body portion adapted to be exposed to the 50 weather when a number of said shingles are laid upon a roof and a weathering projection on the other edge having one of its extremities coinciding with the middle point of said edge.

5. In a shingle, a main body portion, a tab along one edge and at one end of the said body portion having converging sides and being adapted to be exposed to the weather when a number of said shingles are laid upon 60 a roof and a weathering projection on the other edge approximately in line with one end of said tab.

6. In a shingle, a main body portion, a tab along one edge thereof having converging 65 sides and being adapted to be exposed to the

weather when a number of said shingles are laid upon a roof and a weathering projection on the other edge displaced from the central point of said edge a distance equal to substantially one-fourth the amount by which 70 the widest portion of said tab exceeds its narrowest portion.

7. In a shingle, a main body portion, a tab along one edge thereof having converging sides and being adapted to be exposed to the 75 weather when a number of said shingles are laid upon a roof and a weathering projection on the other edge approximately in line with one end of said tab, the ends of said shingle being parallel with each other and also parallel with one side of said tab.

8. In a shingle, a main body portion, a tab along one edge and at one end of the said body portion having converging sides and being adapted to be exposed to the weather 85 when a number of said shingles are laid upon a roof and a weathering projection on the other edge approximately in line with the inner end of said tab, the ends of said shingle being parallel with each other and also parallel with one side of said tab.

9. In a shingle, a main body portion, a tab along one edge thereof having converging sides and being adapted to be exposed to the weather when a number of said shingles are laid upon a roof and a weathering projection on the other edge approximately in line with one end of said tab, the ends of said shingle being parallel with each other and also parallel with one edge of said tab, the edge 100 of said tab and one end of said body portion coinciding.

10. In a shingle, a main body portion, a tab along one edge and at one end of the said body portion having converging sides 105 and being adapted to be exposed to the weather when a number of said shingles are laid upon a roof and a weathering projection on the other edge approximately in line with the inner end of said tab, the ends of said shingle being parallel with each other and also parallel with one edge of said tab, the edge 110 of said tab and one end of said body portion coinciding.

In testimony whereof I affix my signature. 115
CHARLES W. MORTIMER.
